UNITED STATES PATENT OFFICE.

CHARLES CLYDE ROTH, OF BARBERTON, OHIO, ASSIGNOR OF ONE-HALF TO
S. S. FISHER, OF DOYLESTOWN, OHIO.

DEVICE FOR HOLDING GLASS AND SIMILAR ARTICLES IN PLACE.

No. 855,813.

Specification of Letters Patent.

Patented June 4, 1907.

Application filed May 22, 1906. Serial No. 318,172.

To all whom it may concern:

Be it known that I, CHARLES CLYDE ROTH, a citizen of the United States, residing at Barberton, in the county of Summit and State of Ohio, have invented new and useful Improvements in Devices for Holding Glass and Similar Articles in Place, of which the following is a specification.

This invention has relation to devices for uniting two adjacent articles and is peculiarly applicable for holding glass in position in show-case frames, and the object thereof is to provide simple and effective means whereby the translucent material of a show-case may be fixedly secured in place, said means being such that the joint between adjacent parts will be tight as well as completely covered.

Experience has shown that where the glass and frame of a show-case are arranged to lap each other in making a joint between them, considerable difficulty is experienced in making the lapping portions fit perfectly, and hence, in carrying my invention into effect, I employ an efficient yet simple means which obviates the necessity of lapping the parts and also practically insures a perfect union between them.

With the foregoing and other objects in view, the invention consists in the novel construction, combination and arrangement of parts constituting the invention, to be hereinafter referred to and illustrated in the accompanying drawings which form a part of this specification in which is shown the preferred embodiment of the invention, but it is to be understood that changes, variations and modifications can be resorted to which come within the scope of the claims hereunto appended.

In the drawings, in which similar reference numerals indicate like parts in the different figures: Figure 1 is a perspective view of the top portion of a show-case with a portion thereof broken away to better illustrate the invention; and, Fig. 2 is a perspective view of a device used in uniting the glass in position in the frame of a case.

In the drawings, there is shown the upper frame of the show-case in which is mounted a sheet of beveled glass, as being one of the best means for illustrating the adaptability of my device, although, as it will subsequently appear, other objects may be united

together with equal efficiency by means of this invention, and it will also be shown that the glass in the show-case may be perfectly united with the frame even if the same is not provided around its edges with a beveled surface.

Referring more particularly to the drawings, the reference numeral 1 designates the frame of a show-case provided on its outer surface with any ornamental formation which is desired by the maker or user.

In carrying out this invention, I prefer to form on the inner or rear face of the frame 1 a thin but relatively deep rabbet 2. In this rabbet I place the device which constitutes the main portion of this invention, by the use of which the peculiarly desirable characteristics of the invention are obtained. This device consists of an approximately T-shaped strip 3, preferably of metal. This strip 3 may be constructed in various shapes, sizes and conformations without departing in any manner from the scope of this invention. In the drawings, this strip 3 consists of a head portion 4 the upper portion of which is preferably convex in cross-section, and from which depends a web 5. This web may be made with parallel side faces or may be tapering as shown in Fig. 2; but in either event it is provided with openings 6 through which may be passed screws or pins for attaching it in position. The under faces of the head portion 4 of this strip are preferably made concave, although they may, if desired, be made flat and at approximately right angles to the web portion 5.

One of the side portions of the head 4 is preferably arranged to project laterally from the web portion 5 a slightly greater distance than the other. In placing this strip 3 in position, the laterally narrower portion of the head 4 is so placed as to engage the top face of the frame 1 and is held against the same firmly during its placing in position, so that the joint between them will be as perfect as possible. The strip 3 is then secured fixedly in position by means of nails or screws passed through the openings 6 into the frame 1. A sheet of glass 7 is then placed in position by raising the same from below until it encounters the overhanging edge of the head 4 so firmly as to insure an approximately perfect union therewith. This strip 3 will be formed of such material and of such a size

as to be capable of bending slightly in order that the head portion thereof may adapt itself to any slight inequalities which may exist on the portions of the frame or glass which its edges contact with, without in any manner displacing the strip or appreciably distorting the same. When the glass has been placed in position as just stated, a stop 8 of suitable material is pressed upwardly 10 against the under side of the glass with sufficient firmness to maintain the engagement of the glass with the strip, and the stop is then secured in position by nails or screws which enter that portion of the inner face of 15 the frame 1 below the rabbet 2. Of course in assembling a show-case such as is illustrated in the drawings, all the strips 3 will be fastened before the glass is placed in position, so that the strips 3 may be placed in 20 position approximately simultaneously.

From the foregoing it will be seen that this device will work with equal efficiency where the bevel, shown in the drawings, is omitted from the glass, and this device will be equally 25 efficient in joining together other articles. It will be further stated, that if desired, the rabbet 2 may be omitted and the strip 3 secured to the inner face of the frame 1; however, this is not the desired or preferred construction, but is simply mentioned to illustrate the adaptability of this device for the purpose hereinbefore described.

What I claim and desire to secure by Letters Patent, is:—

35 1. The combination with a suitable support and means for securing a body thereto, said means comprising a T-shaped member secured to said support and having one side of the top thereof abutting against the upper 40 face of the support and the other side of the top thereof overlapping and engaging one face of said body, a retaining strip, and means engaging the said support for holding said strip snugly against the other face of 45 said body whereby the other face of said body is brought into close contact with the head of said member.

2. A plate glass retaining device comprising a T-shaped member having the vertical 50 portion thereof provided with openings through which is adapted to extend hold-fast devices for securing the member to a suitable support, the horizontal portion of said member adapted to overlap the glass plate and 55 the support, and a retaining strip abutting against the support and vertical portion of

said member and adapted to engage the glass plate for holding it snugly against the horizontal portion of the member, said retaining strip provided with openings through which is adapted to extend hold-fast devices for retaining said strip in position.

3. Means for securing a sheet of glass in position comprising a T-shaped member adapted to be detachably secured to the inner side of a suitable support and having one side of its top engaging the upper surface of the sheet of glass and its other side the top of the support, and a vertically-extending flat strip adapted to be secured to one side of the support to which the T-shaped member is secured, abut against one side of the vertically-extending portion of said member and have its top edge bear against the lower surface of the glass sheet, thereby in connection with the T-shaped member connecting the glass sheet to the support.

4. Means for securing a sheet of glass in position comprising a T-shaped member adapted to have the vertical portion thereof abut against the inner side of the support to which the glass is to be secured and further having one side of its top engaging the upper surface of the sheet of glass and the other side thereof the top of the support, and a vertically-extending flat strip adapted to be secured to the inner side of said support and abut against one side of the vertically-extending portion of said member and have its top edge bear against the lower surface of the 90 glass sheet, thereby in connection with said member secure the sheet to the support.

5. Means for securing a sheet of glass in position comprising a member adapted to abut against the inner side of the support to 95 which the glass is to be connected and having one side of its top overlapping the sheet of glass, and a vertically-extending flat strip adapted to be secured to the inner side of the support against which the member abuts, 100 abut against said member, thereby retaining it in position and have its top edge engage the lower face of the glass sheet thereby in connection with the overlapping portion of said member secure the glass in position.

In testimony whereof I have hereunto set my hand in presence of two subscribing witnesses.

CHARLES CLYDE ROTH.
